US00D968733S

(12) **United States Design Patent** (10) **Patent No.:** **US D968,733 S**
Maniff et al. (45) **Date of Patent:** **** Nov. 1, 2022**

(54) **COVER**

(71) Applicant: **Maniff Creations, Inc.**, Stevenson Ranch, CA (US)

(72) Inventors: **Jonathan Maniff**, Stevenson Ranch, CA (US); **Francesca Maniff**, Stevenson Ranch, CA (US)

(73) Assignee: **Maniff Creations, Inc.**, Stevenson Ranch, CA (US)

(**) Term: **15 Years**

(21) Appl. No.: **29/739,597**

(22) Filed: **Jun. 26, 2020**

(51) LOC (13) Cl. **15-05**

(52) U.S. Cl.

USPC **D32/25**; D9/451

(58) **Field of Classification Search**

USPC D9/414-426, 428-435, 500, 503, 504, D9/439, 442, 452, 502, 607, 612-615, D9/617, 695, 696, 723, 724, 737, 739, D9/741, 742, 755, 756, 772, 774, D9/776-779, 436, 441, 444, 445, 447, D9/451, 454, 499; D7/601, 602, 538, D7/540, 387, 392.1, 396.2; D3/216, 217; D32/21, 25, 32, 31

CPC .. A63H 3/00; A63H 3/003; A47L 7/00; A47L 9/00; A47L 7/0085; A47L 2201/00

(57) **CLAIM**

We claim the ornamental design for a cover, as shown and described.

DESCRIPTION

FIG. 1 is an upper perspective view of a cover; FIG. 2 is a lower perspective view of the design shown in FIG. 1;

FIG. 3 is a front plan view of the design shown in FIG. 1; FIG. 4 is a rear plan view of the design shown in FIG. 1; FIG. 5 is a left side plan view of the design shown in FIG. 1;

FIG. 6 is a right side plan view of the design shown in FIG. 1;

FIG. 7 is a top plan view of the design shown in FIG. 1; and, FIG. 8 is a bottom plan view of the design shown in FIG. 1. The broken lines shown represent unclaimed subject matter and form no part of the claimed design. The shade lines shown represent surface shading and not surface ornamentation, color, or material type.

1 Claim, 8 Drawing Sheets
